UNITED STATES PATENT OFFICE.

H. C. ALFORD, OF MINOOKA, ILLINOIS.

WASHING-MACHINE.

Specification of Letters Patent No. 31,431, dated February 12, 1861.

To all whom it may concern:

Be it known that I, H. C. ALFORD, of Minooka, in the county of Grundy and State of Illinois, have invented a new and 5 Improved Washing-Machine; and I do hereby declare that the following is a full, clear, and exact description of the same, reference being had to the accompanying drawing, forming a part of this specification, in which—

Figure 1 represents a longitudinal, vertical section of my invention; the line $\alpha\alpha$ Fig. 2, indicating the plane of section. Fig. 2, is a plan or top view of the same.

15 Similar letters of reference in both views indicate corresponding parts.

The object of this invention is to facilitate the washing of clothes in such machines, which have a segmental slotted concave working in the interior of a semi-cylindrical swinging tub.

20 My improvement consists of a peculiar arrangement of parts, so formed that by imparting an oscillating motion to the tub the concave is caused to oscillate in an opposite direction, leaving at the same time the concave free to bear down upon the clothes with its full weight during the 25 whole operation.

30 To enable those skilled in the art to make and use my invention I will proceed to describe its construction and operation, with reference to the drawing.

The semi-cylindrical tub A is suspended 35 from the levers B, which are secured to the sides of the tub and which oscillate on pivots a . The pivots have their bearings in the frame C and they extend through notches in the top edges of the tub to the interior 40 of the same and into the ends of the oscillating bar D. This bar is provided in its middle with a socket b that forms the guide for the stem E, the lower end of which is firmly secured to the concave F. This 45 concave consists of two segmental side rails b' which are connected by slats or rollers c said side rails being of such a height that they bear on the corrugated bottom of the tub without allowing the slats or rollers c

to come in contact with the same. The stem 50 E passes up through the socket of the guide bar D and through the socket d of the swivel bar G which has its bearings in the upper ends of two arms H. The lower ends of these arms are connected by means of 55 pivots e to the upper ends of the levers B and they (the arms) pass through mortises on the upper cross-bars of the frame C. Pins f passing through the upper cross bars of the frame and through slots g in the 60 arms H, form the guides for the latter.

A handle I on the end of the tub A serves to impart to the same the desired motion.

The operation is as follows: A small quantity of water and soap sud is poured 65 into the tub, and the clothes to be washed are placed under the concave F, which bears down on the same with its full weight, the stem E having perfect liberty to rise and fall in the sockets b and d . By these means 70 the concave adjusts itself to the quantity of clothes placed into the tub. An oscillating motion is now imparted to said tub and by the peculiar arrangement of the levers B and arms H, the concave assumes a motion 75 in a direction opposite to that in which the tub moves, and at the same time said concave, being perfectly free to rise and fall, adjusts itself to the surface of the clothes. A slight motion of the tub is sufficient to 80 carry the concave over the entire surface of the clothes and the washing is effected in an easy and simple manner and without the least injury to the fabrics.

Having thus fully described my invention, what I claim as new and desire to secure by Letters Patent is—

The arrangement of the oscillating bar G, slotted arms H and hinged levers B with the oscillating bar D, stem E, oscillating 90 rubber F, and oscillating tub A, in the manner and for the purposes herein shown and described.

H. C. ALFORD.
